CONTROL VALVE MECHANISM

Werner F. Boldt, Clayton, Mo., assignor to
Wagner Electric Corporation, St. Louis, Mo., a
corporation of Delaware

Application May 18, 1938, Serial No. 208,560

16 Claims. (Cl. 303—54)

My invention relates to valve mechanism and more particularly to control valve mechanism for placing a source of fluid pressure or vacuum in communication with a movable member to be operated, as for example, the piston of a fluid motor.

One of the objects of my invention is to produce an improved control valve mechanism which will meter the fluid pressure or vacuum which is caused to be effective on the movable member which is to be operated.

Another object of my invention is to produce a control valve mechanism in which the valve element employed to connect the actuated member to the source of pressure or suction and the valve element employed to connect the actuated member to the exhaust or atmosphere are unseated by a movement in the direction of flow of the fluid and against a biasing means and to so control the biasing means that the pressure on one element can be increased and the pressure on the other element decreased in equal increments.

Still another object of my invention is to provide means in combination with the above valve mechanism which will produce a reactive effect noticeable by the operator in manipulations to vary the pressure or suction effective on the member being operated.

Other objects of my invention will become apparent from the following description taken in connection with the accompanying drawings in which Figure 1 is a cross-sectional view of a valve mechanism embodying my invention and adapted for use in a fluid pressure operated system; Figure 2 is a cross-sectional view of a valve mechanism similar to that shown in Figure 1 but adapted for use in a vacuum-operated system; Figure 3 is a cross-sectional view of a valve mechanism similar to Figure 1 but embodying means for producing a reaction on the member controlled by the operator; and Figure 4 is a cross-sectional view taken on the line 4—4 of Figure 3.

Referring to Figure 1, numeral 1 indicates the casing of the valve mechanism within which is a chamber 2 adapted to be connected to the source of pressure by an inlet port 3, a passage 4 and a conduit 5. The source of pressure for the valve mechanism shown is intended to be compressed air but it is to be understood that other fluids under pressure may be employed. The casing 1 is also provided with an exhaust port 6 in alignment with the inlet port 3 and this exhaust port is in communication with chamber

2 by means of a passage 7. The chamber 2 in the casing is closed by a hollow end cap 8 secured to the casing, and connected to the chamber by a passage in the cap is a conduit 9 placing the chamber in communication with the member to be operated, as for example, a power cylinder for applying a braking assembly.

A reciprocable member 10 is supported by the casing and has one end projecting into chamber 2 upon which is mounted a lateral extending arm 11. The other end of the reciprocable member projects to the exterior of the casing and has mounted thereon a laterally extending arm 12. A seal comprising a packing 13, a spring 14 and an expanding member 15 prevents leakage of 15 fluid past the reciprocable member.

The inlet port 3 is formed with a valve seat 16 and cooperating therewith is a valve element 17 which is so positioned as to be unseated by movement in the direction of flow of fluid under pressure through the inlet port from the source of pressure to chamber 2. The valve element is held in position on its seat by a coil spring 18 interposed between it and arm 11 carried by the inner end of the reciprocable member 10.

The exhaust port 6 is also provided with a valve seat 19 for cooperation with a valve element 20 which is so positioned as to be movable off the seat in the direction of flow of fluid through the exhaust port from the chamber to the exterior of the casing. The valve element 20 is held upon its seat by a coil spring 21 interposed between it and arm 12 carried by the exterior end of the reciprocable member.

The valve springs 18 and 21 are preferably identical in construction and characteristics and when the reciprocable member is in a position where arms 11 and 12 are equal distances from the valve elements 17 and 20, respectively, the springs will maintain the valve elements on their seats with the same pressure. The reciprocable member, however, is normally biased by a spring 22 to a position wherein spring 21 acting on the exhaust valve element 20 will be completely expanded and will exert no pressure or only a negligible pressure on the valve element. The spring 22 is interposed between the shoulder 23 on the reciprocable member and a suitable portion 24 of the casing which acts as a bearing for the reciprocable member. The normal position 50 of the reciprocable member is determined by the engagement of arm 11 with portion 25 of the casing.

The reciprocable member also carries a pin 26 cooperating with a slot 27 in the casing to thereby 55

prevent the reciprocable member from having relative rotation with respect to the casing. The exterior end of the reciprocable member and the exhaust port valve structure are enclosed by a 5 suitable housing 28 secured to the main casing. The reciprocable member is operated by a suitable lever or pedal 29 connected to the reciprocable member by a rod 30 extending through an opening 31 in housing 28, which opening is of 10 sufficient size to permit the free passage from the housing of any air which may be exhausted through the exhaust port 6.

The strength of springs 18 and 21 for the 15 valve elements is so chosen that the springs when compressed will maintain the valve elements seated against the maximum pressure which may be exerted thereon tending to unseat them. In other words, if the maximum fluid pressure is 100 pounds per square inch, for example, the 20 spring 18 will be of sufficient strength to hold the valve element 17 seated and prevent fluid under pressure from passing from the source of pressure to chamber 2 when the reciprocable member is in the position shown in Figure 1. Spring 21, 25 since it is identical with spring 18, will also be of sufficient strength to maintain the valve element 20 seated and prevent the fluid under maximum pressure from passing through the exhaust port when the reciprocable member is 30 moved to its extreme right position.

When the valve mechanism is in the position shown in Figure 1, spring 18 will be compressed and valve element 17 will prevent fluid under pressure from entering the chamber from the 35 source of pressure and since spring 21 is not exerting any pressure on valve element 20, there will not be any fluid under pressure in chamber 2 and the fluid motor which is to be operated. When it is desired to apply pressure to the member 40 to be operated, the reciprocable member 10 is moved to the right. This will cause spring 21 to begin to exert pressure on valve element 20 and spring 18 to apply less pressure to valve element 17. The increment of increase of pressure on valve element 20 is equal to the increment of decrease of pressure on valve element 17. When the pressure on the valve element is decreased sufficiently to permit the fluid under pressure from the source of pressure to unseat 45 valve element 17, fluid under pressure will flow into chamber 2 until the pressure therein plus the spring pressure will be sufficient to close valve element 17. The fluid pressure now in chamber 2 will not be able to be exhausted from 50 the chamber through exhaust port 6 because valve element 20 is held upon its seat by a pressure which is greater than the pressure which the fluid in chamber 2 is exerting on the valve element tending to unseat it.

55 Continued movement of the reciprocable member to the right will cause the pressure on valve element 17 to be further decreased a given amount and the pressure on valve element 20 to be simultaneously increased a like amount. As the pressure on valve element 17 decreases, more fluid under pressure will be capable of entering chamber 2 and thus become effective on the member which is connected to conduit 9. When the reciprocable element has reached the end of 60 its travel to the right, spring 18 will become totally expanded and the pressure on valve element 17 will be negligible. The pressure of the fluid in the chamber will now be the same as that of the pressure source.

65 When it is desired to exhaust the fluid under

pressure from chamber 2 and the fluid-operated member connected to conduit 9, the reciprocable member is allowed to move to the left under the action of spring 22. This will decrease the pressure on valve element 20 and simultaneously increase the pressure on valve element 17. As the pressure on valve element 20 decreases, the fluid under pressure on chamber 2 will be exhausted, the amount depending upon the pressure which is being exerted on the valve element by spring 21. When the reciprocable element has been returned to its normal inoperative position, as shown in Figure 1, spring 21 will exert no substantial pressure on the valve element and under these conditions, all of the fluid under pressure in chamber 2 will be exhausted. During the movement of the reciprocable member to the left, no fluid will be able to pass valve element 17 since the fluid under pressure in chamber 2 plus the pressure exerted by spring 18 will maintain this valve 2 seated.

During the operation of the valve mechanism the fluid under pressure in chamber 2 will exert some pressure on the end of the reciprocable member 10 tending to force it to the left. This pressure varies with the pressure of the fluid in the chamber and thus produces a variable reaction on the operator. In the construction shown the reaction is not great due to the small diameter of the reciprocable member but if a greater reaction is desired, it can be secured by increasing the diameter of the reciprocable member.

From the foregoing description it is apparent that I have constructed a control valve mechanism permitting fluid under pressure to be applied to an operating member as desired. The pressure acting on the operating member can be increased or decreased in very small increments which is a very important feature since it permits the member to be applied and released very gradually.

Referring to Figure 2, I have disclosed my invention embodied in a valve mechanism for a vacuum-operated system. The casing member 32 is formed with a suction port 33 which is connected to the source of suction by the passage 34 and the conduit 35. The port 33 communicates with a chamber 36 in a second casing member 37 secured to the casing member 32. The chamber 36 is in communication by a conduit 38 with a member to be operated, as for example, a vacuum motor. The casing member 32 is also provided with an atmospheric port 39 which is in communication with chamber 36 by a passage 40. The atmospheric port is in alignment with the suction port 33. The valve casing 32 has mounted thereon a reciprocable rod 41 which extends into chamber 36 and carries an arm 42. The other end of rod 41 projects to the exterior of casing 32 and carries an arm 43.

The suction port 33 has a valve seat 44 and cooperating therewith is a valve element 45 having a fluted stem 46 slidable in the suction port. The valve element is positioned to be movable off seat 44 in the direction corresponding to the flow of fluid from chamber 36 to the source of suction which may be a manifold of an internal combustion engine. A coil spring 47 connects the valve element 45 to arm 42. The atmospheric port 39 has a valve seat 48 and cooperating therewith is a valve element 49 having a fluted stem 50 slidable in the port. The valve element 49 is positioned to be movable off seat 48 in the direction of flow of fluid from the atmosphere to

chamber 36. A spring 51 connects the valve element 49 to arm 43. The reciprocable rod 41 is normally biased to the right-hand end of its travel by a spring 52 interposed between casing member 32 and arm 42, arm 43 under these conditions abutting the casing member 32. The reciprocable rod is actuated by rod 53 carried by casing member 37 and the outer end of this rod is engaged by an operating element 54 which may 10 be a lever or a pedal. A perforated cap 54' encloses the exterior end of rod 41, arm 43 and spring 51.

In the normal inoperative position of the valve mechanism, rod 41 will be in the right-hand end of its travel. Spring 51 will be fully contracted and no substantial pressure will be exerted to hold valve element 49 seated. Spring 52 under these conditions will be under tension and it will be exerting maximum effort to maintain the valve element 49 seated. The springs 41 and 51 are of identical construction and characteristics and they are of such strength that when expanded, the valve elements will not be unseated by the action of suction.

25 To connect the source of suction to the suction motor, rod 41 is moved to the left and when in its extreme left position, as shown in Figure 2, the source of suction is capable of applying its maximum effect to operate the vacuum motor. Atmospheric pressure will be unable to pass through the atmospheric port 39 into chamber 36 because spring 51 is exerting its pressure upon the valve element 49.

The general operation of the structure shown 35 in Figure 2 is similar to that shown in Figure 1 except that vacuum is employed instead of fluid under pressure and to accommodate this change, the valve elements and the valve seats are reversed. The amount of air that is drawn from 40 chamber 36 and the vacuum motor by the source of suction can be regulated to the desired extent by the forward movement of rod 41 in the same manner as the pressure is regulated by the movement of the reciprocable member 10 in the previously described valve. Also, the amount of air 45 from the atmosphere that is admitted to chamber 36 to release the suction motor can be regulated by the extent of return movement of rod 41.

50 Referring to Figures 3 and 4, I have shown a valve mechanism for use with a fluid pressure system which is very similar to that disclosed in Figure 1 but has the additional feature of a spring interposed between the actuating member 55 and the longitudinally reciprocable member, which spring is adapted to be acted upon by a piston carried by the reciprocable member and subject to the same fluid pressure which is effective on the member which is operated, as for 55 example, the power cylinder. The valve mechanism shown comprises a casing 55 provided with a fluid receiving chamber 56 having an inlet port 57 connected to a source of pressure by means of a passage 58 and a conduit 59. The chamber 56 is also connected to an exhaust port 60 by means of a passage 61. The chamber is connected to the member to be operated, such as a power cylinder, by means of conduit 62 communicating with passage 61. There is also provided a cover plate 63 for closing the end of the casing, the cover plate forming one wall of chamber 56.

The casing 55 is formed with a bore 64 within which is mounted the reciprocable member 65.

75 The inner end of this member has mounted

thereon an arm 66, the hub of which is in the form of a piston, and the other end of the reciprocable member is formed with an integral arm 67. A suitable packing element 68 seals the reciprocable member in the bore and prevents leakage of fluid from chamber 56.

The inlet port has associated therewith a seat 69 and cooperating with the seat is a valve element 70 which is movable off the seat in the direction of flow of fluid from the source of pressure to chamber 56. A spring 71 is interposed between arm 66 and the valve element. The exhaust port 60 has associated therewith a suitable seat 72 and cooperating with this seat is a valve element 73 which is movable off the seat 15 in the direction of flow of fluid from the chamber 56 to the atmosphere. A coil spring 74 is interposed between arm 67 on the reciprocable member and valve element 73. The springs 71 and 74 are of like construction and have the same 20 characteristics and cooperate with their respective valve elements in the manner already set forth with respect to the construction shown in Figure 1.

The reciprocable member 65 is biased to its 25 normal inoperative position by a coil spring 75, thereby causing arm 66 to abut casing 55 as a stop and placing spring 71 under maximum compression. Under these conditions, coil spring 74 will not be compressed and, therefore, apply only 30 a negligible pressure to the valve element 73. The reciprocable element is actuated by an actuating member 76 which has bearing in a cap member 77 having an exhaust opening 78. Interposed between the actuating member and the reciprocable member is a coil spring 79 which is in an uncomressed condition when the actuating member is not actuated and the reciprocable member is in its normal inoperative position as shown in Figure 3. The reciprocable member 40 is prevented from rotation relative to the casing by a slot 80 and a pin 81.

In operation, movement of the reciprocable member 65 to the right will cause spring 71 to apply less pressure to the valve element 70 and 45 the spring 74 to apply greater pressure to the valve element 73 whereby fluid under pressure will be admitted to chamber 56 and the power cylinder in a manner already described with respect to the mechanism of Figure 1. Return 50 movement of the reciprocable member to the left will cause spring 71 to be compressed and spring 74 to expand whereby the fluid under pressure in chamber 56 and the power cylinder will be exhausted to atmosphere. The amount 55 of fluid under pressure applied or released can be in small increments since the movement of the reciprocable member causes the springs to increase and decrease the pressures on the valve elements in like increments.

60 The use of spring 79 between actuating member 76 and the reciprocable member 65 in combination with the large end area of the reciprocable member which is subject to the pressure of the fluid in chamber 56 results in a reaction 65 on the actuating member 76. Since spring 79 has a rapid buildup, it will be compressed very little as the actuating member is initially operated to move the reciprocable member to the right. As fluid under pressure is admitted to 70 chamber 56, it will be effective on the end of the reciprocable member and will cause the reciprocable member to float slightly to the left for a given position of the actuating member, thereby compressing spring 79 and causing a pressure 75

to be applied to the actuating member opposing the force applied to said member. This reaction force will be proportional to the pressure of the fluid in the chamber and, therefore, the pressure acting on the power cylinder, thus giving the operator what is commonly known as "feel." In other words, the greater the pressure being applied, the greater will be the reaction on the actuating member and consequently the operator. Spring 79, by permitting the reciprocable member to be initially moved beyond the position it finally assumes after the fluid under pressure is admitted to chamber 56, results in a more rapid application of pressure since spring 71 will apply less pressure to valve element 70 during the admission of fluid than it does after fluid has been admitted.

Being aware of the possibility of other modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In a control valve mechanism, a casing provided with ports for supplying fluid to and exhausting it from a chamber, a valve associated with each port and movable off its seat in the direction of flow of fluid through the port, means associated with each valve for applying pressure thereto to hold it in closed position, means for varying the pressure by which the means holds the supply port valve closed, and means subject to differential fluid pressures for causing a reactive effect on the last named means independently of the valves and the means for applying pressure thereto.

2. In a control valve mechanism, a casing provided with ports for supplying fluid to and exhausting it from a chamber, a valve associated with each port and movable off its seat in the direction of flow of fluid through the port, a biasing means associated with each valve for applying pressure thereto to hold it in closed position, means for varying the pressure exerted by each biasing means to hold the valves closed and means subject to the fluid pressure in said chamber for causing a reactive effect on said last named means independently of the valves and their biasing means.

3. In a control valve mechanism, a casing provided with ports for supplying fluid to and exhausting it from a chamber, a valve associated with each port and movable off its seat in the direction of flow of fluid through the port, a spring associated with each of said valves and applying pressure tending to hold it seated, means for increasing the pressure applied by one of said springs and simultaneously reducing the pressure applied by the other, said springs and said means being so related that the amount of increased pressure is substantially equal to the amount of reduced pressure, and a piston associated with said last named means and subject to the fluid pressure in the chamber for causing a reactive effect on said last named means.

4. In a control valve mechanism, a casing provided with ports for supplying fluid to and exhausting it from a chamber, a valve associated with each port and movable off its seat in the direction of flow of fluid through the port, said ports being aligned and the opening movements of the valves being in opposite directions, a

spring associated with each of the said valves, a member connected to each spring for controlling the pressure the spring applies to its valve, and means for moving the members in unison and in the same direction whereby an increasing pressure will be applied by one spring and a decreasing pressure will be applied by the other spring.

5. In a control valve mechanism, a casing provided with ports for supplying fluid to and exhausting it from a chamber, a valve associated with each port and movable off its seat in the direction of flow of fluid through the port, said ports being aligned and the opening movements of the valves being in opposite directions, a spring associated with each of said valves, a member connected to each spring for controlling the pressure the spring applies to its valve, means for moving the members in unison and in the same direction whereby an increasing pressure will be applied by one spring and a decreasing pressure will be applied by the other spring, and a third spring associated with the last named means for biasing it to a position in which one of the valve springs will be applying a maximum pressure and the other a minimum pressure.

6. In a control valve mechanism, a casing provided with ports for supplying fluid to and exhausting it from a chamber, a valve associated with each port and movable off its seat in the direction of flow of fluid through the port, a compression spring associated with each valve and applying pressure tending to hold it seated, and a longitudinally movable member carrying an abutment for each spring, said abutments, valves and springs being so related that longitudinal movement of the movable member increases the compression of one spring and reduces the compression of the other.

7. In a control valve mechanism for fluid pressure, a casing provided with aligned inlet and exhaust ports and an outlet port, a valve element for the inlet port and positioned for movement off its seat in the direction of flow of fluid from the inlet port to the outlet port, a coil spring for seating the valve element, a second valve element for the exhaust port and positioned for movement off its seat in the direction of flow of fluid from the outlet port to the exhaust port, a coil spring for seating the second valve element, a reciprocable member, abutments on said reciprocable member for engaging the coil springs, said abutments being so spaced apart that when the reciprocable member is at one end of its travel the spring of the inlet valve element will be compressed and the spring of the exhaust valve element uncompressed and when the reciprocable member is at the other end of its travel the spring of the inlet valve element will be uncompressed and the spring of the exhaust valve element compressed, and means for reciprocating the reciprocable element.

8. In a control valve mechanism for fluid pressure, a casing provided with aligned inlet and exhaust ports and an outlet port, a valve element for the inlet port and positioned for movement off its seat in the direction of flow of fluid from the inlet port to the outlet port, a coil spring for seating the valve element, a second valve element for the exhaust port and positioned for movement off its seat in the direction of flow of fluid from the outlet port to the exhaust port, a coil spring for seating the second valve element, a reciprocable mem-

ber, abutments on said reciprocable member for engaging the coil springs, said abutments being so spaced apart that when the reciprocable member is at one end of its travel the spring of the inlet valve element will be compressed and the spring of the exhaust valve element uncompressed and when the reciprocable member is at the other end of its travel the spring of the inlet valve element will be uncompressed and the 10 spring of the exhaust valve element compressed, a spring for normally biasing the reciprocable element to one end of its travel, and means for moving the reciprocable member against the last named biasing spring.

16. 9. In a control valve mechanism, a casing provided with ports for supplying fluid to and exhausting it from a chamber, a valve associated with each port and movable off its seat in the direction of flow of fluid through the port, means 20 for applying pressures to said valves tending to hold them closed, said means being so associated with the valves that the pressure applied to one valve may be increased and the pressure applied to the other valve simultaneously reduced, an operator-operated member, and means associated with said means and subject to differential fluid pressures for causing a reactive effect on the operator-operated member.

10. In a control valve mechanism, a casing 30 provided with ports for supplying fluid to and exhausting it from a chamber, a valve associated with each port and movable off its seat in the direction of flow of fluid through the port, a spring associated with each of said valves and applying pressure tending to hold it seated, means for increasing the pressure applied by one of said springs and simultaneously reducing the pressure applied by the other, an operator-operated member, and means associated with 35 said means and subject to differential fluid pressures for causing a reactive effect on the operator-operated member.

11. In a control valve mechanism, a casing 40 provided with aligned ports for supplying fluid to and exhausting it from a chamber, valve elements associated with the ports and each movable off its seat in the direction of flow of fluid through the port, springs for holding the valve elements seated, a reciprocable member, means 45 carried by the reciprocable member for causing one of the springs to apply an increasing pressure to its valve element and simultaneously permitting the other spring to apply a decreasing pressure to its valve element, spring means co-operating with the reciprocable member for normally causing it to assume a position wherein the valve element for one of the ports is maintained seated under maximum pressure and the valve element for the other port is maintained seated under minimum pressure, and means associated 50 with the reciprocable member and subject to the differential pressure between the pressure of the fluid in the casing and the atmospheric pressure for causing a reaction to movement of the reciprocable member.

12. In a control valve mechanism, a casing 55 provided with ports for supplying fluid to and exhausting it from a chamber, valve elements associated with the ports and each movable off its seat in the direction of flow of fluid through the port, means for simultaneously causing an increasing closing pressure to be exerted on one of the valves and a decreasing closing pressure to be exerted on the other valve, operator-operated means for actuating said means, and means

associated with the first named means and subject to the differential pressure between the fluid pressure in the casing and the atmospheric pressure for causing a reaction on the operator-operated means.

13. In a control valve mechanism for fluid pressure, a casing provided with aligned inlet and exhaust ports and an outlet port, a valve element for the inlet port and positioned for movement off its seat in the direction of flow of fluid from the inlet port to the outlet port, a coil spring for seating the valve element, a second valve element for the exhaust port and positioned for movement off its seat in the direction of flow of fluid from the outlet port to the exhaust port, a coil spring for seating the second valve element, a reciprocable member, abutments on said reciprocable member for engaging the coil springs, said abutments being so spaced apart that when the reciprocable member is at one end of its travel the spring of the inlet valve element will be compressed and the spring of the exhaust valve element uncompressed and when the reciprocable member is at the other end of its travel the spring of the inlet valve element will be uncompressed and the spring of the exhaust valve element compressed, a spring for normally biasing the reciprocable element to one end of its travel, means for moving the reciprocable member against the last named biasing spring, and a piston carried by the reciprocable element and being subject to the pressure of the fluid in the casing.

14. In a control valve mechanism for fluid pressure, a casing provided with aligned inlet 35 and exhaust ports and an outlet port, a valve element for the inlet port and positioned for movement off its seat in the direction of flow of fluid from the inlet port to the outlet port, a coil spring for seating the valve element, a second 40 valve element for the exhaust port and positioned for movement off its seat in the direction of flow of fluid from the outlet port to the exhaust port, a coil spring for seating the second valve element, a reciprocable member, abutments on said reciprocable member for engaging the coil springs, said abutments being so spaced apart that when the reciprocable member is at one end of its travel the spring of the inlet valve element will be compressed and the spring of the exhaust valve element uncompressed and when the reciprocable member is at the other end of its travel the spring of the inlet valve element will be uncompressed and the spring of the exhaust valve element compressed, a spring 50 for normally biasing the reciprocable element to one end of its travel, means for moving the reciprocable member against the last named biasing spring, a spring interposed between said last named means and the reciprocable member, and a piston carried by the reciprocable element and being subject to the pressure of the fluid in the casing.

15. In a control valve mechanism, a casing provided with a chamber having a port for connection with a source of suction, a second port for connection with the atmosphere and a third port for connection with a suction-operated member, a valve element associated with the first named port and positioned for movement 7 off its seat in the direction of flow of fluid from the chamber to the source of suction, a valve element associated with the second port and positioned for movement off its seat in the direction of flow of fluid from the atmosphere to the 7

- chamber, the opening movements of said valve elements being in opposite directions, a reciprocable member, and tension means between each of the valve elements and the reciprocable member, said tension means being so associated with the reciprocable member and the valve elements and having such characteristics that one of the valve elements will be held seated with a maximum pressure and the other valve element will be seated with substantially no pressure when the reciprocable member is at one end of its travel and when the reciprocable member is at the other end of its travel the pressure on the valve elements will be reversed.
16. In a control valve mechanism, a casing provided with a chamber having a port for connection with a source of suction, a second port aligned with the first named port for connection with the atmosphere and a third port for connection with a suction-operated motor, a valve element associated with the first named port and

positioned for movement off its seat in the direction of flow of fluid from the chamber to the source of suction, a valve element associated with the second port and positioned for movement off its seat in the direction of flow of fluid from the atmosphere to the chamber, the opening movements of said valve elements being in opposite directions, a reciprocable member, arms carried by the member and positioned on opposite sides of the aligned ports, tension springs of like characteristics for connecting the valves to the arms of the reciprocable member, means for normally biasing the reciprocable member to a position where the spring connected to the valve element of the first port will exert a maximum pressure thereon to hold it seated and the spring connected to the valve element of the second port will exert substantially no pressure thereon tending to hold it seated, and means for moving the reciprocable member against its biasing means. 15 20

WERNER F. BOLDT.
